UNITED STATES PATENT OFFICE.

WALTER F. BROWN, OF PROVIDENCE, RHODE ISLAND.

CUT-OFF-VALVE GEAR.

SPECIFICATION forming part of Letters Patent No. 402,557, dated May 7, 1889.

Application filed October 29, 1888. Serial No. 289,366. (No model.)

To all whom it may concern:

Be it known that I, WALTER F. BROWN, a citizen of the United States, residing at Providence, in the county of Providence and State 5 of Rhode Island, have invented certain new and useful Improvements in Cut-Off-Valve Gears; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 My invention relates to the valve-gear of automatic cut-off engines of the four-valve or "Corliss" type; and it consists, essentially, of a loosely-mounted double-acting or cam-grooved disk connected with the governor, in 20 combination with the main operating-arm or hook-lever provided with a tripping-lever engaging said cam, and a valve-arm or steam-lever secured to the valve-stem and arranged to engage the tripping-lever, all as will be 25 more fully hereinafter set forth and claimed.

Heretofore, or at least usually in engines of the class referred to, the construction has been such that the act of cutting off or releasing the steam-valve imposes considerable extra 30 work upon the governor for the time being, by reason of the thrust or resistance due to the engagement of the tripping-lever with the governor-connected "knock-off." A natural result of such construction is that the gov- 35 ernor is continually fluctuating independently of the changes or variations in the work or "load" upon the engine. Another objection to such former construction is that it necessitates the employment of a spring for return- 40 ing the tripping-lever to its normal position after it has released the valve. The use of a spring for this purpose is especially objection- 45 able, because it increases the work upon the governor by an amount equal to the resist- 50 ance of the spring in returning the tripping-lever, as stated. The use of such springs also produces considerable noise in working.

The object I have in view is to provide an engine with a positive hooking-on device in 55 which springs are entirely dispensed with. It also combines an arrangement for positively closing the steam-valves, the construction be-

ing such that the work upon the governor in cutting off is greatly reduced, thereby rendering it more sensitive. In designing my improvements I have also studied to reduce the cost of manufacture. 55

Another advantage of my improvement is that the fulcrum of the hook and tripping-lever is located somewhat below the line of pressure of the contact-surfaces of the hook-plates, thereby nearly balancing or neutralizing the resistance required to trip the valve. A slight preponderance in leverage, however, is given to the hook, by means of which the latter is 60 inclined to engage the hook-plate of the steam-lever rather than to disengage it. By reason of this arrangement the work imposed upon the governor in releasing or tripping the valve is actually reduced to a minimum. 70

In the accompanying three sheets of drawings, Figure 1, Sheet 1, is a side elevation of a portion of a cut-off-valve gear embodying my improvements, the parts being in the normal or "hooked-on" position. Fig. 2 is an 75 end view, the several rods or connections being broken off. Fig. 3 is an end view, in reduced scale, of the cam-grooved double-acting cam detached. Fig. 4 is a similarly-reduced view of the hook-lever adapted to be actuated 80 by the wrist-plate. Fig. 5, Sheet 2, is an end view substantially as shown in Fig. 2, the relation of the parts corresponding to the unhooked or tripped position. Fig. 6 is a perspective view of a rectangular steel block 85 adapted to be attached to the steam-lever. Fig. 7 is a similar view of a bolt having a square steel-headed plate adapted to be mounted in the hook or latch to engage said steel block. Fig. 8 is a sectional view taken 90 through the head of the bolt. Fig. 9 is a side elevation of a Corliss cylinder, showing the manner of mounting and connecting my improved valve-releasing gear. Fig. 10, Sheet 95 3, is a side elevation showing my improvement reversed in the manner of its application. Fig. 11 is an end view of the same, the parts being hooked on and in the act of moving to uncover the steam-port; and Fig. 12 is a side view, detached, of the bolt-carrying arm 100 of the hook and the steel block of the steam-lever, showing more clearly that the line of contact of the surfaces of the hook-plates is above the center or fulcrum of the arm.

A more specific description of my present invention is as follows: I would first state, however, that my improvements are more particularly adapted to be applied to a "four-valve engine." A cylinder of this class is indicated by C², Fig. 9, the general arrangement and manner of actuating the valves being substantially the same as characteristic of the well-known Corliss engine. A wrist-plate, 5 W, is pivoted to the center of the cylinder, the same having a pin, E', adapted to be jointed to a rod taking its motion from the eccentric, as usual.

E, Fig. 1, designates the back cover or bonnet for the steam-valve, and s indicates the valve-stem mounted to vibrate in said bonnet. The outer portion of the bonnet is turned off to form a bearing for the loosely-mounted hook-lever A and the double-acting 10 governor-connected disk C. To the outer or free end of the valve-stem is keyed the steam-arm or bell-crank lever B. One arm, b', of this lever has its outer end provided with a pin, b², to which is jointed the drop-rod d. 15 The purpose of the drop-rod is as common—that is, it serves, in combination with a weighted piston mounted in a vacuum-chamber in falling, to quickly close the steam-valve immediately succeeding the tripping of the steam-arm by the action of the governor, &c. The other arm, b, (which is nearly vertical,) of the lever B is planed across at its lower end, b³, to form an elongated seat or abutment, b², against which a face of the rectangular steel 20 block n is adapted to bear. The arm b is drilled parallel with the seat b², to receive a headed bolt or screw, o, having the said block n secured to its lower end, the bolt being so fitted that it may move freely up and down in 25 the arm b. The outer or front face of the block n is adapted to engage a vertical face of the steel plate r, mounted in the hook f. By means of this construction and arrangement the line of pressure of the arm B and hook f 30 in working is substantially in the same plane and well within the bearing of the loosely-mounted main or hook lever.

The lever A, as before stated, is mounted to 35 freely vibrate on the hub of the back bonnet. The upper portion or arm, a, of said lever has a pin, c', mounted therein, to which is jointed a link or connection, l, also jointed to and receiving motion from the wrist-plate W. The lower portion, a', of the lever A is provided 40 with an elongated hub, c, at its free end, the same being drilled to receive a short shaft, m, to which the two parts f t, constituting the releasing-lever, are secured. The hook portion f, which lies nearly horizontal in its normal position, is provided at its free end with 45 a square-headed steel bolt, p'.

In Figs. 7 and 8 the head r is represented as a square plate, through which said bolt passes. This construction readily permits of 50 the substitution of a new plate when necessary. A portion of the hook f is enlarged, as at f', contiguous to the hub, thereby, in con-

nection with a similarly-arranged surface formed on the back of the block-carrying portion of the steam-arm, serving, when the two 70 surfaces are in engagement, to positively close the valve; or, in other words, in case the drop-rod fails from any cause to drop the proper distance, the action of the lever A, as it approaches the end of its stroke, forces the surface f' against the steam-arm, and thus insures the complete closing of the valve. The tripping-lever t is secured to the rear end of the shaft m, the same having its free end provided with a truck-roll, t², arranged to travel 80 in a cam-shaped slot, e. By means of this arrangement it will be seen that the axial movement of the shaft m is coincident with that of the roll t² in its passage along the slot e.

C indicates the cam-disk, the same being 85 loosely mounted on the hub of the bonnet E and at the rear of the lever A. The disk is provided with a double-acting cam-groove, e, the latter being so arranged with reference to the center or axis of the disk as to produce 90 three concentric sections united by the actual cam-surfaces i i'. (See Fig. 3, &c.) The cam-disk is connected with the usual governor mechanism by a link or rod, g, jointed to the disk, whereby the cam is axially vibrated as 95 required, to effect the proper point for releasing the valve. We will assume now that an engine is provided with my improvements, and that it is arranged to revolve in a forward direction, the position of the several 100 parts constituting the valve-gear being substantially as represented in Fig. 9, wherein the back steam-valve is in the act of being opened to uncover the port to force the piston ahead on its forward stroke, (the front 105 steam-port meanwhile being covered by the tripped valve,) the corresponding position of the steam-arm, &c., being represented in Fig. 2.

It will be seen by referring to the drawings 110 that the cam-roll t² is in that portion of the groove e nearest the axis of the valve-stem, (or intermediate of the end portions,) thereby 115 acting to maintain the hook f in engagement with the steel block n. The continued movement of the wrist-plate forces the steam-arm B in the arrow direction, thereby uncovering the steam-port, and at the same time lifting the drop-rod d and its connections, the roll t² meanwhile traveling in the center section of 120 the concentric portion of the cam-groove e until it meets the cam-surface i', when the latter causes the tripping-lever to outwardly vibrate upon its axis a distance equal to the cam's offset, thereby unhooking the tripping-lever and releasing the valve, after which the 125 drop-rod, &c., acts to close the steam-port, thus effecting the cut-off.

In case the load upon the engine is reduced 130 the governor will immediately act (for the time being) to vibrate the disk C in a direction contrary to the movement of the connected levers A and B. The conjoint movement of the said parts causes the cam-roll to

pass down the cam-surface i' earlier, thereby releasing the valve, as just described, the relative position of the several parts being substantially as represented in Fig. 5. During the remainder of the stroke of the wrist-plate the roll t^2 will travel idly in the concentric portion of the slot e . Upon the return-stroke of the wrist-plate W the roll will reverse its movement, (the lever B meanwhile remaining stationary.) When the roll reaches and passes upon the said cam-surface i' , the steel plate r will come in contact with and pass under the tripping-block n , the latter, with its bolt o , freely rising and instantly dropping again to its normal position by gravity as soon as the plate p has passed. As the hook-lever A approaches the end of its rearward stroke, the lug f' of the hook f will engage the rear side of the steam-arm (if the port is not already fully lapped by the valve) and force the lever B to travel to its limit. The valve remaining thus closed until the next forward stroke of the wrist-plate causes the tripping-lever, &c., to again act to open the valve, as before described.

In case the governor-belt breaks or the governor becomes inoperative through any cause while the engine is running, the connections g will act to carry the disk C in the extreme opposite direction, (see arrow v , Fig. 2,) thereby causing the roll t^2 to pass down the cam-surface i of the cam-groove, by means of which movement the hook is prevented from engaging the latch-block n and positively preventing the parts from hooking on to open the steam-valve.

It will be seen, Fig. 12, &c., that the axis of the tripping-lever and hook is so arranged with reference to the line of pressure of the hook-plates that the resistance required to trip the valve is nearly balanced. The hook f , however, is given a slight increase in leverage, thereby producing a tendency of the hook-plates to engage each other instead of disengagement. By means of this arrangement of the levers and hook-plates the work of releasing or tripping the valve by the governor is reduced to a minimum.

I would state as another advantage resulting from the employment of my improvement that in the event of serious wear upon the roll t^2 , or even in case it should break while the engine is in operation, the action of the cam, &c., will force the hook f from the block n and prevent their re-engagement.

In Figs. 10 and 11 the arrangement of the tripping-levers and cam C is reversed, the several arms or levers being slightly changed in their construction to correspond with the new conditions or relations. The action of the parts is, however, practically the same as hereinbefore described with reference to the arrangement shown in Fig. 2, &c.

In the specification and claims I have termed the cam a "disk." It is obvious, however, that the actual contour or periphery of the disk itself need not be circular necessa-

rily, although the latter form is more symmetrical.

I claim as my invention—

1. The governor-actuated double-acting cam-grooved disk and the pivotally-mounted hook and tripping-lever connected with said cam, and a steam-arm having a latch-block adapted to engage said hook, substantially as hereinbefore described, and for the purpose set forth. 70

2. In a cut-off valve, the combination, with the governor-actuated double-acting cam-grooved disk, of a pivotally-mounted tripping-lever and hook taking its axial movement from said cam, substantially as shown and hereinbefore described. 80

3. In a cut-off-valve gear, the combination, with the steam-arm and hook-lever, of a loosely-mounted tripping-lever and hook traveling in unison with said hook-lever, and a loosely-mounted double-acting cam-grooved disk actuated by the governor and having an arm of the said tripping-lever connected with and worked by said groove of the cam, substantially as hereinbefore described, and for the purpose specified. 85

4. In a releasing or cut-off-valve gear, the combination, with a steam-arm having a drop-rod and a loosely-mounted latch-block, as n , carried by said arm, of a pivotally-mounted hook arranged to engage said latch-block, a working or hook lever, as A , carrying the tripping-lever and hook and oscillated by the engine, and a positive-acting or cam-grooved disk, as C , actuated by the governor and having the tripping-lever engaging said cam, whereby the movements of the lever A and cam, individually or conjointly, act to oscillate the tripping-lever, substantially as hereinbefore described; and for the purpose specified. 95

5. In a cut-off-valve gear, the combination, with the loosely-mounted governor-actuated double-acting cam-grooved disk hereinbefore described, of a suitably-mounted hook, as f , axially vibrated by means of said cam and arranged to engage the steam-arm, &c., of the valve-gear, substantially as set forth, and for the purpose stated. 100

6. In a cut-off-valve gear, the combination, with the loosely-mounted governor-actuated cam-grooved disk, as C , of the pivotally-mounted tripping-lever t , vibrated by said cam, a loosely-mounted hook-lever, A , carrying the tripping-lever, a fixed steam-arm, B , provided with a drop-rod and latch-block, as n , mounted to move up and down in the arm, and a hook, f , secured to and moving in unison with the said tripping-lever and provided with a lug, as f' , to engage the steam-arm to positively close the steam-valve, the whole combined, arranged, and operating substantially as shown and described. 110

7. In a cut-off-valve gear, the arrangement of the axis of the tripping-lever and hook below the line of pressure of the contact-surface of the hook-plates, substantially as shown, 120

whereby the resistance or work required to trip the valve is nearly balanced, thereby also relieving the governor and rendering it more sensitive in working, substantially as hereinbefore described.

5. In a cut-off-valve gear, the combination of a governor-actuated cam-grooved disk, C, and a pivotally-mounted tripping-lever and hook positively vibrated in each direction by

being connected to the cam-groove, substantially as shown and set forth.

In testimony whereof I have affixed my signature in presence of two witnesses.

WALTER F. BROWN.
